DESIGN FOR A REFRIGERATED DISPLAY CABINET

Cyrus F. Hoffman, Trenton, N. J., assignor to
V. V. Hill & Company, Inc., Trenton, N. J., a
corporation of New Jersey

Application June 11, 1942, Serial No. 107,176

Term of patent 14 years

To all whom it may concern:

Be it known that I, Cyrus F. Hoffman, a citizen of the United States, residing at Trenton, in the county of Mercer and State of New Jersey, have invented a new, original, and ornamental Design for a Refrigerated Display Cabinet, of which the following is a specification, reference being had to the accompanying drawing, forming part thereof.

Fig. 1 is a perspective view of a refrigerated display cabinet embodying my design;

Fig. 2 is an end elevational view of the display cabinet shown in Fig. 1;

Fig. 3 is an end elevational view of the display cabinet shown in Fig. 1, with parts broken away to show the appearance of the interior of the display cabinet more clearly; and

Fig. 4 is a top plan view of the display cabinet illustrated in Fig. 1.

I claim:

The ornamental design for a refrigerated display cabinet, as shown and described.

CYRUS F. HOFFMAN.
